FUEL OIL CARBURETOR BURNER

Filed March 31, 1945

2 SHEETS—SHEET 2

*Inventor
Joseph Sonntag*

By Louis Sheldon Att'y.

has an end 94 passing through the inverted cup 50 and a washer 96 and is threaded into a plenum chamber 98 of substantially L-shape in cross-section secured as at 100 to the sleeve 76. The chamber 98 has a vertical wall 101 between which and the bottom of the channel ring 62 outwardly of the holes 64 in said ring is disposed suitable sealing means comprising a gasket 102 to seal the juncture. A nut 103 threaded to the outer end of the perforated tube 90 is drawn tight against the elbow 84 to prevent leakage. The corrugations 72 in the split ring 70 provide alternate vertical passages 104 and 106 communicating with the holes 64 and 68 in the channel rings 62 and 66.

It will now be apparent that the liquid fuel entering the elbow arm 86 will be drawn by the engine suction through the perforations 92 into the tube 90, to the plenum chamber 98, thence through the openings 64, 68, 104 and 106 to and along the prongs 74 and to the tops of the channel rings 62 and 66 at the bases of the prongs.

The split ring 70 serves as a flame ring and is preferably made of metal of high electrical resistance, such as molybdenum, of a thickness on the order of about 0.005", more or less. The ends of the flame ring are folded back as shown at 108 and 110 (Fig. 2) one or more times to provide sufficient thickness for tapped holes 112 and 114 for the reception of screws 116 and 118, respectively. The screw 116 is also threaded in a wall of the outer channel ring 62 and thereby grounds one end of the flame ring 70. The screw 118 passes over the outer channel ring 62 and is insulated from the housing 50 and body 20 by a sleeve 120 and is connected by a wire 122 to the movable contact 123 of the starter button switch 124, the other contact 125 of which is connected with the ignition switch 126 and thence with the hot side of the automobile battery 128. As usual the starter switch also controls the starting motor 130. A wire 132 leading from the starter switch contact 123 is connected to the primary side 134 of a spark intensifier 136, the secondary 137 of which is connected by a wire 138 to a spark plug 140 screwed into and thereby grounded by the body 20, said plug having its points 142 and 144 preferably disposed adjacent a prong 74 (Fig. 4).

The sleeve 76 may rest on a screen or perforated disc 146 (Fig. 1) in the base cap 53. Below the disc 146 is a rotatable valve plate 148 having a series of holes 150 adapted to be placed in and out of complete register with a similar series of ports 152 in the base cap 53 and leading to the atmosphere, the sleeve 76 substantially overlying the centers of the holes and ports. The bottom of the sleeve 76 is preferably perforated as at 154 so that the air will pass upwardly with equal force on both sides thereof, to insure perfect combustion of the fuel at both sides of the prongs 74. The base cap 53 has an upstanding sleeve boss 155 about which is disposed a washer spacing the disc 146 from the plate 148.

Assuming the ignition switch 126 to be closed, then when the starter button 123 is depressed, the starter switch 124 closes, whereupon the motor 130 turns over the engine, which draws fuel up the sides of the generator flame ring 70 and the prongs 74 thereof and air through the discs 146 and 148 to the opposite sides of the prongs. The closing of the starter switch also completes a circuit through the flame ring 70, which, due to its high electrical resistance, becomes heated and vaporizes the oil in contact therewith, particularly below the prongs, since at the prongs the resistance to the flow of the

current is less and hence the prongs are not heated as much. The closing of the starter switch also completes a circuit which energizes the spark intensifier 136, whereupon a spark jumps between the spark plug points 142 and 144, igniting the combustible mixture of the vaporized oil and the air also drawn upward through the openings 150 and 152 by the engine suction. The resulting flame vaporizes the fuel along the prongs, and the air supports combustion of that vapor also. The continued upward flow of the air and fuel due to the engine suction and vaporization of the fuel on the sides of the flame ring maintains a continuous flame, so that the starter button can be released promptly. The heater chamber 52 is thereby heated to and maintained at a high temperature to thereby heat the conversion chamber 54 for vaporizing the fuel to be consumed by the engine, as will appear.

The rate of flow of air through the ports 150 and 152 is controlled by the valve plate 148. To this end, I form an arcuate slot 157 in the base cap 53 and dispose therein a pin 158 secured to the valve plate. The pin 158 has a lateral arm with a yoke 160 in which an adjusting screw 164 is received, collars 166 fixed on the screw being disposed on opposite sides of the yoke. The screw is threaded in spaced lugs 168 depending from the base 53, and has a convenient knob 170. It is obvious that turning of the knob will rotate the valve plate 148, and thus vary the extent of registration of the openings 150 with the openings 152.

To conduct engine fuel to the converter 54, I connect a pipe 172 (Figs. 1 and 2) to the float chamber outlet 78 and to a hollow boss 174 branching from a sleeve 176 which may be integral with the base cap 53. Within the sleeve 176 is a valve plunger 178 engageable with a valve seat member 182 threaded within the base cap sleeve boss 155. A spring 186 under compression between the lower part of the plunger and a plug 188 closing the bottom of the sleeve 176 tends to seat the plunger and thus close the valve. A hollow branch 190 on the sleeve 176 supports a rock shaft 192 carrying an arm 194 projecting between shoulders 196 on the valve plunger 178, the shaft projecting out of the branch 190 and being there connected to a crank arm 198 connected by a link 200 with an actuating lever 202 secured to a shaft 204 which also controls the throttle valve 34. The valve plunger 178 is narrowly fluted as at 206 to afford passages for the flow of fuel in small streams when the valve is open.

Within the collar 76 and over the perforated disc 146 is a preferably imperforate baffle cup 210 disposed about the sleeve boss 155 and spaced from said disc as by a washer 212, the cup being held in place as by a nut 214 threaded on the boss. The cup 210 serves as a baffle, causing air which rises into the collar 76 to be guided toward the outer periphery of the cup so as to pass up in the restricted space or throat 216 en route to the inner side of the series of prongs 74 of the flame ring 70, thus providing a venturi effect.

Spaced above the cup 210 is a relatively deep cup 220 which may be held on the sleeve boss 155 as by a flange 222 on the valve seat member 182 and be riveted as at 224 or otherwise suitably secured to the top 226 of the cup housing 50. The cup 220 is preferably imperforate up to a level above the tops of the prongs 74 to insure that substantially all of the air drawn up will be available for the support of combus-

tion at the prongs and to insure that the flame will be confined to the heater chamber 52 and not enter the conversion chamber 54. From said level the cup 220 has a circumferential series of slots 228 serving as a flue through which the products of combustion may escape from the flame or heater chamber 52 and be drawn down, to heat the wall of and thence enter the engine fuel vaporizing chamber 54, as will appear.

The top 226 of the housing 50 has an opening defined by a flange 230 in which is tightly held or secured a sleeve 232 having a bell 234 at its bottom to which is secured a hollow imperforate cylinder 240. Within the lower part of the cylinder 240 is snugly fitted a perforated annular plate 242 having small holes 244 and held against creeping as by split spring rings 246 expanding against the cylinder.

Resting on the flange 222 is a frusto-conical cup 248 on whose rim 250 rest the arms 252 of a spider 254 whose hub 256 rests on the valve seat member flange 222 and is there secured as by a screw 258 threaded in said seat member. Access to the screw is gained through the central opening 259 in the perforated plate 242. Tongues 260 bent up from the free ends of the spider arms engage the inner surface of the lower rim of the cylinder 240. Secured as at 264 to and depending from outer portions of the spider arms 252 are baffle members 266. The valve seat member 182 is formed with fine capillary passages 268 inclined outward and upward toward the baffles 266.

The oil entering the valve seat member 182 when the valve plunger 178 is unseated can escape only through the passages 268, whence it is drawn by the suction of the engine, such passages being preferably quite small so that the oil will issue therefrom in fine streams and impinge on the baffles 266 to produce a spray or mist. The mist then passes laterally on opposite sides of each spider arm 252 and rises in the spaces between adjacent arms and then passes through the holes 244 in the plate 242, these holes being quite small to further break up any oil globules in the mist. The products of the combustion in the combustion or heater chamber 52 are drawn by the engine suction radially inward through the slots 228, thence down between the cup 220 and the cylinder 240, thereby heating the cylinder 240, and into contact with the fuel mist formed at the spider 254, and mixes and rises with the mist, imparting heat to the perforated disc 242 also. These gases are quite hot and, coupled with the heat from the cylinder 240 and disc 242, have the immediate effect, upon contact with the mist, of completely vaporizing the same so as to render it suitable, when mixed with the air in the mixing chamber 28, for combustion in the engine.

The burning which takes place in the combustion chamber 52 has another salutary effect. It liberates hydrogen, which unites with the oxygen in the air drawn in, to form water vapor. This vapor is drawn with the other gases of combustion into the vaporizing or conversion chamber 54 and becomes commingled with the mixture to be burned in the engine. It is a well known fact that water vapor acts as a catalyst to bring about substantially complete combustion of a fuel mixture in the cylinder of an engine, so that there will be no residue, any free carbon liberated in the engine combustion being united with the oxygen present to pass off as carbon dioxide.

I prefer to provide a high resistance primer heating wire 280, say one made of Nichrome, molybdenum, tungsten or other suitable material, in the path of movement of the fuel oil to be burned in the engine, to vaporize a sufficient quantity of the fuel to enable the engine to turn over on its own power immediately after closing of the starter switch 124 so as to cause the engine to produce enough suction in the heating chamber to stimulate and hasten ignition of the vapor produced in the combustion chamber 52 of my carburetor. When the starter button 123 is depressed in the conventional or other manner the engine will be turned over and at the same time the current will heat the flame ring 70 and generate the first vapor which will be ignited by the spark from the spark plug 140 associated with the flame ring 70. At the same instant that the starter switch 124 is closed, current will pass through the coil 280 and heat it sufficiently to generate or vaporize the first gas, and the incoming air from the inlet 22, to be burned by the engine, causing the engine to turn over in the usual manner on its own power. Such operation of the engine, being relatively more rapid than when due to the starting motor, will produce increased suction in the carburetor and bring about enough draft to continuously maintain the flame at the flame ring 70. Ignition at the flame ring takes place after the starter switch is closed for a second or so, and thereupon this switch may be opened, whereupon of course all current in the primer coil 280, spark plug 140 and flame ring 70 ceases to flow although the flame continues heating the fuel in the conversion or vaporizing chamber 54, the engine continuing to run without further aid of electricity as far as the carburetor is concerned.

One end of the coil 280 may be secured and therefore grounded by the screw 258. The upper part of the coil may pass through an insulating grommet 282 and then continue as at 284 to the starter switch contact 123 so that when the starter switch 124 is closed a circuit is completed through the coil.

When the ignition is shut off, the engine of course stops and so does the flame in the heater 52 due to lack of suction necessary to draw air to support combustion of the flame.

While there is shown and described herein certain specific structure embodying the invention, it will be manifest to those skilled in the art that various modifications and rearrangements of the parts may be made without departing from the spirit and scope of the invention, and that the same is not limited to the particular forms herein disclosed, except insofar as indicated by the appended claims.

I claim:

1. In a fuel oil carburetor, a burner comprising a member having a channel adapted to contain fuel oil, the surface of said channel being non-metallic and heat resistant, and means for heating oil in said channel to a state in which the oil, in the presence of oxygen, is ignitable by a spark, said means comprising an electrical resistor disposed in and extending along and at least substantially throughout the depth of, and of less cross-sectional area than, and having portions between and spaced from the sides of, said channel, the difference between said cross-sectional areas being relatively slight, affording fissures for the passage of oil between said resistor and the sides of said channel, means for

providing a supply of fuel oil to said channel, and means affording a supply of air adjacent the mouth of said channel.

2. In a fuel oil carburetor, a burner comprising a member having a channel adapted to contain fuel oil, the surface of said channel being non-metallic and heat resistant, and means for heating oil in said channel to a state in which the oil, in the presence of oxygen, is ignitable by a spark, said means comprising an electrical resistor disposed in and extending along and at least substantially throughout the depth of, and of less cross-sectional area than, and having portions between and spaced from the sides of, said channel, the difference between said cross-sectional areas being relatively slight, affording fissures for the passage of oil between said resistor and the sides of said channel, means for providing a supply of fuel oil to said channel, means affording a supply of air adjacent the mouth of said channel, and means for providing a spark adjacent the mouth of said channel.

3. In a fuel oil carburetor, a burner comprising a member having an annular channel of substantially greater height than width and with its mouth uppermost, said member having one or more holes to admit fuel oil to the bottom of said channel, the surface of said channel being non-metallic and heat resistant, means for heating oil in said channel to a state in which, in the presence of oxygen, the oil is ignitable by a spark, said means comprising an electrical resistor disposed in and substantially throughout the length and depth of said channel and projecting out of said mouth and of less cross-sectional area than said channel and having portions between and spaced from the sides of said channel, the difference between said cross-sectional areas being relatively slight, affording fissures for the passage of oil between said resistor and the sides of said channel, means for providing a supply of oil to said channel, means affording a supply of air at both sides of the outwardly projecting portion of said resistor, and means for providing a spark adjacent said projecting portion of said resistor.

4. A fuel oil carburetor burner including a member having a refractory-surfaced channel adapted to contain fuel oil, said surface being electrically non-conductive, and means for heating oil in said channel to a state in which the oil, in the presence of oxygen, is ignitable by a spark, said means comprising an electrical resistor disposed in and extending along and engaging longitudinally spaced portions of the surface of said channel.

5. A fuel oil carburetor burner including a member having an elongated refractory-surfaced channel adapted to contain fuel oil, said surface being electrically non-conductive, and means for contacting and heating oil in said channel to a state in which the oil, in the presence of oxygen, is ignitable by a spark, said means comprising an electrical resistor disposed in and extending along and engaging longitudinally spaced portions of the surface of and projecting out of said channel.

6. A fuel oil carburetor burner including a member having an elongated refractory-surfaced channel adapted to contain fuel oil, said surface being electrically non-conductive, and means for heating oil in said channel to a state in which the oil, in the presence of oxygen, is ignitable by a spark, said means comprising an electrical re-

sistor disposed in and extending along and substantially throughout the depth of said channel and engaging longitudinally spaced portions of the channel surface.

5 7. In a fuel oil carburetor, a burner comprising a member having a refractory-surfaced channel open at the top and adapted to contain fuel oil, said surface being electrically non-conductive, and means for heating oil in said channel to a state in which, in the presence of oxygen, it is ignitable by a spark, said means comprising an electrical resistor seated in said channel and engaged with the channel surface and supported solely by said member.

15 8. In a fuel oil carburetor, a burner comprising a member having a refractory-surfaced channel adapted to contain fuel oil, said surface being electrically non-conductive, and means for heating oil in said channel to a state in which the oil, in the presence of oxygen, is ignitable by a spark, said means comprising an electrical resistor disposed in and extending along and at least substantially throughout the depth of, and having portions engaging and other portions between and slightly spaced from the sides of, said channel, affording fissures for the passage of oil between said resistor and the sides of said channel.

25 9. In a fuel oil carburetor, a burner comprising a member having a refractory-surfaced channel open at the top and adapted to contain fuel oil, said surface being electrically non-conductive and means for heating oil in said channel to a state in which the oil, in the presence of oxygen, is ignitable by a spark, said means comprising an electrical resistor in the form of a metal band engaging the channel surface and extending along said channel, the faces of said band facing the sides of said channel, portions of said faces being slightly spaced from the sides of said channel, affording fissures for the passage of oil between said faces and the sides of said channel.

35 10. In a fuel oil carburetor, a burner comprising a member having a refractory-surfaced channel adapted to contain fuel oil, said surface being electrically non-conductive, and means for heating oil in said channel to a state in which the oil, in the presence of oxygen, is ignitable by a spark, said means comprising an electrical resistor in the form of a metal band engaging the channel surface and extending in and along said channel, the faces of said band facing the sides of said channel, portions of said faces being slightly spaced from the sides of said channel, affording fissures for the passage of oil between said faces and the sides of said channel, said band having a series of prongs projecting free of said channel.

45 11. In a fuel oil carburetor, a burner comprising a metal support, a refractory electrically non-conductive ring mounted on said support and having an annular channel open at the top and adapted to contain fuel oil, said support and ring having communicating passages for admitting oil to said channel, and means for heating oil in said channel to a state in which, in the presence of oxygen, it is ignitable by a spark, said means comprising a substantially annular electrical resistor seated in said channel and having longitudinally spaced portions frictionally engaged with said ring, the remainder of said resistor being spaced from the sides of said channel, said portions being of substantially less area than said remainder of said resistor.

55 12. In a fuel oil carburetor, a burner comprising a metal support having an annular groove,

a refractory electrically non-conductive ring nested in said groove and having an annular channel open at the top and adapted to contain fuel oil, said support and ring having communicating passages for admitting oil to said channel, and means for heating oil in said channel to a state in which, in the presence of oxygen, it is ignitable by a spark, said means comprising an electrical resistor in the form of a substantially annular metal band seated in said channel and 10 insulated by said ring from said support, said band having longitudinally spaced portions frictionally engaged with said ring.

13. In a fuel oil carburetor, a burner comprising a metal member having an annular groove 15 open at the top, a refractory electrically non-conductive ring nested in said groove and having an annular channel open at the top and adapted to contain fuel oil, said member and ring having communicating passages for admitting oil to said channel, and means for heating oil in said channel to a state in which, in the presence of oxygen, it is ignitable by a spark, said means comprising an electrical resistor in the form of a substantially annular metal band seated in said channel and insulated by said ring from said member, said band having corrugations extending widthwise thereof and frictionally engaged with and retained by said ring, the areas of engagement between said band and said ring being substantially smaller than the unengaged areas of said band, the thickness of said band being slightly less than the width of said channel.

14. In a fuel oil carburetor, a burner comprising a horizontal refractory electrically non-conductive ring having an annular horizontal channel open at the top and adapted to contain fuel oil, and means for heating oil in said channel to 35

a state in which, in the presence of oxygen, it is ignitable by a spark, said means comprising a substantially annular electrical resistor frictionally engaged with and retained by longitudinally spaced portions of said ring and seated in said channel, the thickness of said resistor being less than the width of said channel and the major portion of said resistor being spaced from but close to the sides of said channel so that the oil may contact the major portion of said resistor to promote rapid heating of the oil.
